UNITED STATES PATENT OFFICE.

HENRY E. MAURER, JR., OF SPRINGFIELD, ILLINOIS, ASSIGNOR, BY DIRECT AND MESNE ASSIGNMENTS, OF ONE-THIRD TO HARRY L. IDE AND ONE-THIRD TO R. W. IDE, BOTH OF SPRINGFIELD, ILLINOIS.

APPARATUS FOR DISPENSING LIQUIDS.

1,262,077.

Specification of Letters Patent. Patented Apr. 9, 1918.

Application filed October 8, 1917. Serial No. 195,220.

To all whom it may concern:

Be it known that I, HENRY E. MAURER, Jr., citizen of the United States, residing at Springfield, in the county of Sangamon and State of Illinois, have invented a certain new and useful Improvement in Apparatus for Dispensing Liquids, of which the following is a full, clear, concise, and exact description.

My invention relates to apparatus for dispensing liquids and has been successfully employed in dispensing gasoline to users of automobiles. My invention has for a general object the improvement of means whereby liquid dispensing containers are filled and whereby the filling operation is automatically discontinued.

My invention has a number of other objects among which are an improvement in the construction of the containers; an improved interrelation between filling pipes and vacuum pipes that project into the containers for the purpose of filling the same; and improved means for effecting illumination in the region of the containers.

All of the objects of my invention will be fully set forth by a description of the preferred embodiment of the invention shown by the accompanying drawings and in which Figure 1 is a view, somewhat diagrammatic, illustrating parts of the apparatus in elevation and part in section; Fig. 2 is a view in elevation, partially in section, illustrating the upper portion of the apparatus; Fig. 3 is a view on line 3—3 of Fig. 2; and Fig. 4 is a view on line 4—4 of Fig. 2.

Like parts are indicated by similar characters of reference throughout the different figures.

The containers 1 are desirably in the form of inverted glass bottles. As I have practised my invention these bottles have been of five gallons capacity each. Gage marks 2 may be suitably provided, as upon the bottles, corresponding to other measured quantities within the bottles. The bottle necks 3 are received in annular seats 4 whose tubular extensions 5 are screwed into the upper ends of pipe fittings 6. The contents of the bottles or containers 1 are emptied from such containers through the elements 5 and 6 whose bores are in communication with the interiors of the containers. Cross connection piping 7 connects the pipe fittings 6.

The piping 7 includes a T 8 that connects the piping 7 with a delivery pipe or hose 9. Hand valves 10, each individual to a container 1, permit or cutoff communication between the containers and the piping 7. If the measured quantity of liquid that is in one container is alone to be supplied to the delivery pipe 9 the valve 10 individual to that container is alone opened but if contents from both containers are to be supplied to the delivery pipe 9 both valves 10 are opened. Liquid that is to be conveyed to the containers is discharged into the containers through filling pipes 11 that extend into the liquid supply tank 12 nearly to the bottom thereof. Each pipe 11 passes upwardly through a pipe fitting 6, the tubular extension connected with such pipe fitting and the neck of the bottle that overlies the elements 5 and 6, sufficient space intervening between such pipe 11 and the elements 3, 5 and 6 to permit of the free discharge flow of liquid from the bottle. The enlarged lower portion of each fitting 6 receives packing 13 that closes the space between the fitting 6 and the filling pipe 11 passing therethrough. Each packing 13 is forced into tight sealing engagement with the associate filling pipe 11 and the pipe fitting 6 by means of the cylindrical plug 14 through the bore in which the corresponding pipe 11 passes. This plug 14 carries wings 15 while the pipe fitting 6 carries wings 16. Bolts 17 are in threaded engagement with the wings 15 and pass loosely through holes in the wings 16. By turning the heads 18 of the bolts the cylindrical plug 14 is forced tightly against the corresponding packing 13 to insure the tight sealing engagement of such packing 13 with the pipe 11 that passes therethrough and also with the corresponding fitting 6. Each filling pipe 11 terminates near the top of the container receiving it, such container being completely filled when the liquid supplied thereto through such pipe reaches the upper end of the pipe. The extent to which the pipe projects into the container receiving it is adjusted or calibrated by means of the bolts 17 and nuts 19, 20 thereon. Said bolts pass loosely through wings 21 projecting from the elbow 22 included in each pipe 11. When the nuts 19 and 20 are withdrawn from the wings 21 the corresponding pipe 11 may be moved up and down to adjust its

height within the associate container where-
after the nuts 19 and 20 are brought into
clamping engagement with the wings 21
that are interposed between said nuts. The
vacuum tank 23 is provided with means,
later more fully to be set forth, for estab-
lishing communication between it and the
upper portions of the containers 1 whenever
liquid is to be supplied from the tank 12
10 through the filling pipes 11 to the contain-
ers. A framework 24 supports the fittings 6
that are in supporting relation to the con-
tainers. The upper side 25 of the frame-
work 24 carries the upright rods 26 that are
15 in supporting relation to the 3-shaped frame
27 that surrounds the upper ends of the
containers 1 and overlies the curved upper
edges of these containers. The frame 27 is
lined by a gasket 28. The rods 26 pass
20 through the frame 27 and are threaded
where they pass through such frame. Nuts
29 are in threaded engagement with the
threaded portions of the rods 26 and are
employed to clamp the necks of the bottles
25 1 firmly upon their seats 4. The packing 28
yieldingly maintains the bottle necks in en-
gagement with their seats 4 and serves to
permit expansion and contraction of the bot-
tles. The rods 26 support the canopy or
20 hood 30 clear of and above the bottles. The
top of the canopy is provided with a circular
flanged opening 31 midway between the
ends of the canopy and directly overlying
the space between the bottles. A globular
35 dome 32 of translucent or transparent mate-
rial projects upwardly from the canopy and
is disposed over the aforesaid opening 31.
The frame 27 supports a spider 33 which
constitutes a mounting for an electric lamp
34 that is disposed within the dome 32. The
hood or canopy being held clear of the bot-
tles, light from the lamp 34 will not only
pass through the translucent or transparent
dome 32 but will issue downwardly through
45 the opening in the bottom of the dome and
the corresponding opening in the top of the
hood or canopy and will pass not only be-
tween the hood and the bottles thoroughly
to light the space surrounding the apparatus
50 but will also pass through the bottles to en-
able the observer clearly to note the amount
of liquid within the bottles and the extent
to which such liquid is being discharged
through the delivery pipe 9. The vacuum
55 tank 23 thus not only serves its prime func-
tion of exhausting air from the containers
1 but also serves to support the containers,
the canopy or hood, the lighting dome 32,
the lamp within the dome, and the frame-
work 28 that holds the containers in upright
60 positions firmly upon the seats 4. As the
pipes 11 are clamped into engagement with
the fittings 6 through the intermediation of
the plugs 14 and the packing 13 and as the
fittings 6 depend from the tubular exten-
sions 5 of the seats 4, the vacuum tank also
serves to support said pipes 11. Vacuum
pipes 35 are in communication with and are
supported by the vacuum tank 23. These
vacuum pipes terminate in valve seats 36, 70
the seat portions 36 of the pipes 35 being
joined with valve chambers 37. Floats 38
are located within the valve chambers and
carry valves 39 for engagement with the
seats 36 when connection with the vacuum 75
tank is to be cut off, these valves being sepa-
rated from their seats when communication
between the containers and the vacuum tank
is to be established. Continuations 40 of
the vacuum pipes connect the valve cham- 80
bers with the upper portions of the contain-
ers 1. When liquid is to be admitted to the
containers the three-way cocks or valves 41
are thrown to close the ports 42 that lead to
the external atmosphere and to open com- 85
munication between the parts of the pipes 35
upon opposite sides of the valves 41 whereby
the valve chambers 37 are thrown into com-
munication with the vacuum tank. As the
valve chambers are in communication with 90
the upper portions of the containers 1 the
containers are likewise thrown into com-
munication with the vacuum tank. When the
valves 41 are thus thrown to establish com-
munication between the vacuum tank and 95
the upper portions of the containers 1, air
is exhausted from the containers whereupon
liquid from the tank 12 (which liquid is sub-
ject to atmospheric pressure) will flow up-
wardly through the pipes 11 to the levels co- 100
incident with the upper ends of the vacuum
pipes 40, which terminate above the pipes
11. Small portions of this liquid will flow
downwardly through the vacuum pipes 40
into the valve chambers 37 and when re-
ceived in sufficient quantity within said valve
chambers the float 38 will rise to engage the
valves 39 with their seats 36 whereby com- 105
munication between the vacuum tank and
the containers is automatically cut off to 110
cause the cessation of upward flow of liquid
through the pipes 11. When the valves 41
are thrown to break communication between
the valve chambers 37 and the vacuum tank
and to throw these chambers into com- 115
munication with the external atmosphere by way
of the ports 42, air at atmospheric pressure
will find passage into the containers by way
of the valve chambers and the vacuum pipes
40 whereupon the liquid in the containers 120
will fall to the levels defined by the openings
at the upper ends of the filling pipes 11, the
liquid departing from the containers flowing
downwardly through the filling pipes into
the liquid tank 12, the small portions of 125
liquid in the valve chambers and the vacuum
pipes 40 being sucked back into the containers
as the excess liquid descends from the con-
tainers to the limiting levels defined by the
openings in the upper ends of the pipes 11. 130

After the containers are thus filled they may be discharged singly through the pipes 9 to different consumers, the valve 10 pertaining to the container that is to be emptied being opened. If the same consumer desired contents from both containers the valves 10 pertaining to both containers are opened whereupon contents from these containers are free to flow through the single delivery pipe 9 common to such containers.

The extreme upper ends of the filling pipes are closed by the overhanging caps 43 that project over the lateral discharge openings 44 in the filling pipes. The vacuum pipes 40 project through the caps 43 to a sufficient extent above the openings 44. By closing the extreme upper ends of the filling pipes and placing discharge openings in the sides of such pipes the flow of liquid is directed across the containers away from the vacuum pipes so that there is no danger of liquid prematurely finding its way through the vacuum pipes 40 to the valve chambers 37.

The tops of the containers or bottles 1 are concave as indicated at 45. The upper ends of the filling pipes 11 and the vacuum pipes 40 are extended into the peripheral corners at the tops of the containers so as to bring the bottoms of the discharge openings 44 substantially on a level with the most depressed portions of container tops 45. In this way the depressed tops of the containers serve to reduce the swirling action of the liquid flowing from the filling pipes into the containers whereby the possibility of premature entry of liquid into the vacuum pipes 40 and valve chambers 37 is further reduced.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. Liquid dispensing apparatus including a dispensing liquid container; means for introducing liquid into the container; means for exhausting air from the container; a valve for checking the exhaustion of air from the container; a chamber for the valve in communication with the upper portion of the container to receive liquid from such upper container portion, said valve being movable to a checking position by the liquid received in said chamber; and means enabling the discharge of liquid from said container.

2. Liquid dispensing apparatus including a dispensing liquid container; means for introducing liquid into the container at an upper portion thereof; means for exhausting air from the container; a valve for

checking the exhaustion of air from the container; a chamber for the valve in communication with the container to receive liquid therefrom and communicating with the container at a place above the place where liquid is introduced into the container, said valve being movable to a checking position by the liquid received in said chamber; and means enabling the discharge of liquid from said container.

3. Liquid dispensing apparatus including a dispensing liquid container; means for introducing liquid into the container; means in communication with an upper portion of the container for exhausting air from the container; a valve for checking the exhaustion of air from the container; a chamber for the valve in communication with the upper portion of the container to receive liquid from such upper container portion, said valve being movable to a checking position by the liquid received in said chamber; and means enabling the discharge of liquid from said container.

4. Liquid dispensing apparatus including a dispensing liquid container; means for introducing liquid into the container at an upper portion thereof; means in communication with an upper portion of the container for exhausting air from the container; a valve for checking the exhaustion of air from the container; a chamber for the valve in communication with the upper portion of the container to receive liquid therefrom and communicating with the container at a place above the place where liquid is introduced into the container, said valve being movable to a checking position by the liquid received in said chamber; and means enabling the discharge of liquid from said container.

5. Liquid dispensing apparatus including a dispensing liquid container; means for introducing liquid into an upper portion of the container; means in communication with the container at a place above the place where liquid is introduced into the container for exhausting air from the container; a valve for checking the exhaustion of air from the container; a chamber for the valve in communication with the upper portion of the container to receive liquid from such upper container portion, said valve being movable to a checking position by the liquid received in said chamber; and means enabling the discharge of liquid from said container.

6. Liquid dispensing apparatus including a dispensing liquid container; means for introducing liquid into the container at an upper portion thereof; means in communication with the container at a place above the place where liquid is introduced into the container for exhausting air from the container; a valve for checking the exhaus-

tion of air from the container; a chamber for the valve in communication with the container to receive liquid therefrom and communicating with the container also at a 5 place above the place where liquid is introduced into the container, said valve being movable to a checking position by the liquid received in said chamber; and means enabling the discharge of liquid from said 10 container.

7. Liquid dispensing apparatus including an inverted bottle whose top is concave; a filling pipe having a discharge opening at its 15 upper end that defines a level for the liquid that approximates the level of the most depressed portion of the concave top of the bottle; and a vacuum pipe terminating above said level for the liquid.

8. Liquid dispensing apparatus including 20 an inverted bottle whose top is concave; a filling pipe terminating at the peripheral upper corner of the bottle; and a vacuum pipe terminating above the discharge opening in the upper end of the filling pipe. 25

9. Liquid dispensing apparatus including a dispensing liquid container; a filling pipe projecting upwardly into the container and having a closed upper end and a lateral discharge opening adjacent said closed upper 30 end; and a vacuum pipe terminating above the filling pipe.

In witness whereof, I hereunto subscribe my name this 20th day of September, A. D., 1917.

HENRY E. MAURER, JR.
